UNITED STATES PATENT OFFICE.

HENRY K. BENTE, OF SEDALIA, MISSOURI.

VALVE-GEAR.

1,247,923.

Specification of Letters Patent. Patented Nov. 27, 1917.

Application filed March 16, 1914. Serial No. 825,016.

To all whom it may concern:

Be it known that I, HENRY K. BENTE, a citizen of the United States, residing at Sedalia, in the county of Pettis and State of Missouri, have invented a new and useful Valve-Gear of which the following is a specification.

The present invention relates to improvements in valve gears, one object of the invention being the provision of a valve gear by means of which at the beginning of each stroke, the valve is rapidly opened and held in such open position substantially stationary during the introduction and expansion 15 of the pressure fluid or steam so that the driving piston is properly operated with the minimum amount of steam to develop the maximum power, the same being cushioned at the end of the stroke by a certain amount of the retained pressure fluid, so 20 that the piston is operated in a smooth manner and with practically no lost motion.

A further object of the present invention is the provision of a valve gear, the operating member of which is adapted to be connected to the main drive rod so as to have an elliptic movement imparted thereto whereby the valve is operated rapidly to opening or closing position, and retained in either one 30 of said positions substantially stationary during the greater movement of the piston so that a maximum power is exerted and received from the pressure fluid upon the power piston.

A still further object of the present invention is the provision of a valve gear in which the frictional parts are greatly reduced, thereby reducing the power necessary to operate the same so that the maximum efficiency is obtained from the valve gear without any detrimental or impeding effect upon the power piston.

With the foregoing and other objects in view which will appear as the description 45 proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—

Figure 1 is a side elevation illustrating 55 a valve gear embodying the present invention;

Fig. 2 is a detail perspective showing a portion of the structure depicted in Fig. 1;

Fig. 3 is a fragmental perspective showing a modification;

Figs. 4, 5 and 6 are fragmental side elevations showing the arm in adjusted positions;

Fig. 7 is a transverse section taken through the cross head.

In the drawings, the numeral 100 denotes 65 a cylinder of a locomotive engine in which operates a piston 102 connected by means of a piston rod 105 with a cross head 104 mounted to reciprocate in a cross head guide 103. A valve chest 101 is shown, and 70 a valve V operates in the valve chest. A valve rod 50 is connected with the valve V and slides in a standard 19^c erected on the cross head guide 103.

As shown in Fig. 7, the cross head 104 75 carries a pin 39 on which the forward end of a drive rod 40 is mounted to swing. The forward end of the drive rod 40 carries adjusting bolts 41 movable for adjustment in 80 arcuate slots 43 formed in a disk 42 constituting a part of an arm 44 disposed radially with respect to the pin 39. A primary link 46 is pivoted at 45 to the free end of the arm 44.

The invention comprises a pair of sec- 85 ondary links 48 and 51 having a common pivotal connection at 47 with the upper end of the primary link 46. The link 48 is pivoted at 49 to the rear end of the valve rod 50. A plate 54 is erected on the cross head 90 guide 103 and is provided with a curved slot or guide 53 in which moves, for adjustment, a pin 52 in the forward end of the secondary link 51. The lower end of a link 21^b is pivotally supported on the pin 52, 95 the upper end of the link 21^b being pivoted to a bell crank 22^b fulcrumed on a bracket 106 carried by the cross head guide 103. One end of a rod 23^b is pivoted to one arm 100 of the bell crank 22^b, and the other end of the rod 23^b is pivotally connected with an operating lever 24^b.

When the bell crank 22^b is operated by means of the rod 23^b and the lever 24^b, the link 21^b will be raised and lowered, the pin 105 52 moving in the slot or guide 53 of the plate 54, and the position of the secondary link 51, and consequently the position of the primary link 46 being adjusted thereby to regulate the travel of the valve V. The 110 construction is such that the pivotal connection 45 between the primary link 46 and

the arm 44 will describe an ellipse, as hereinbefore mentioned.

In the modification delineated in Fig. 3, the device is characterized by the fact that 5 two standards 19^b support slidably the valve rod 50¹, as distinguished from the single standard 19^c which supports the valve rod 50 in Fig. 1.

In Figs. 4 and 6 the arm 44 is shown forwardly presented, but arranged at different 10 angles with respect to the drive rod 40. In Fig. 5, the arm 44 is shown rearwardly extended and disposed at an acute angle to the drive rod 40.

15. What is claimed is:

1. In a device of the class described, a cylinder; a valve chest; a cross head guide; a cross head operating in the guide; a piston working in the cylinder and connected 20 to the cross head; a drive rod; a connection between the drive rod and the cross head; a radial arm mounted to swing for adjustment on the connection and embodying a free end; means for holding the arm fixed 25 at adjusted angles with respect to the drive rod; a primary link pivoted to the free end of the arm; a pair of secondary links having a common pivotal connection with the primary link; a valve operating in the valve 30 chest and pivoted to one of the secondary links; an auxiliary guide supported on the cross head guide; and an adjusting means under the control of an operator and movable in the auxiliary guide, the other auxiliary 35 link being pivotally connected with the adjusting means.

2. In a device of the class described, a cylinder; a valve chest; a piston working in the 40 cylinder; a valve working in the valve chest; a drive rod operatively connected to the piston; a radial arm mounted

to swing for adjustment on the drive rod and embodying a free end; means for holding the arm fixed at adjusted angles with respect to the drive rod; a primary link 45 pivoted to the free end of the arm; a pair of secondary links pivoted to the primary link, one of the secondary links being pivotally connected to the valve; a fixed arcuate guide; and an adjusting means under 50 the control of an operator and movable in the guide from one fixed position to another, the other secondary link being pivotally connected with the adjusting means.

3. In a device of the class described, a 55 cylinder; a valve chest; a cross head guide; a cross head operating in the guide; a piston working in the cylinder and connected to the cross head; a drive rod; a connection between the drive rod and the cross head; a radial arm mounted to swing for adjustment on the connection and embodying a free end; means for holding the arm fixed at adjusted angles with respect to the drive 60 rod; a primary link pivoted to the free end of the arm; a pair of secondary links pivotally connected with the primary link; a valve operating in the valve chest and pivotally connected with one of the secondary 65 links; an adjusting means under the control of an operator and pivotally connected with the other secondary link; and means coacting with said other secondary link for controlling the movement thereof under the 70 action of the adjusting means.

In testimony that I claim the foregoing as my own, I have hereto affixed my signature in the presence of two witnesses.

HENRY K. BENTE.
